COAXIAL CRIMPING TOOL

Henry William Demler, Sr., Lebanon, Pa., assignor to
AMP Incorporated, Harrisburg, Pa.

Filed Mar. 17, 1964, Ser. No. 79,042

Term of patent 14 years

(Cl. D54—13)

FIGURE 1 is a perspective view of a coaxial crimping tool embodying my new design, shown in the closed position;

FIGURE 2 is a view similar to FIGURE 1 showing the coaxial crimping tool in the open position.

The appearance of the coaxial crimping tool as viewed from the opposite side is substantially identical to that shown in FIGURES 1 and 2.

I claim:

The ornamental design for a coaxial crimping tool, substantially as shown and described.
